Filed May 9, 1975, Ser. No. 575,876

Term of patent 14 years

Int. Cl. D10—04

U.S. Cl. D2—320

FIG. 1 is a bottom plan view of a sole for footwear showing my new design;

FIG. 2 is a right side elevational view thereof;

FIG. 3 is a left side elevational view thereof;

FIG. 4 is a cross-sectional view as taken from line 4—4 of FIG. 1;

FIG. 5 is a cross-sectional view as taken from line 5—5 of FIG. 1;

FIG. 6 is a cross-sectional view as taken from line 6—6 of FIG. 1; and

FIG. 7 is a bottom plan view of another embodiment of my new design of FIG. 1 wherein the inset rear heel portion is also perforated as is the front and side inset, all other views being substantially identical to FIGS. 1—6.

I claim:

The ornamental design for a sole for footwear, substantially as shown and described.
